(57) **CLAIM**

The ornamental design for a removable comfort pad for a bedpan, as shown and described.

DESCRIPTION

FIG. 1 is a top and front perspective view of a removable comfort pad for a bedpan showing my new design, and shown in operative association with a bedpan;

FIG. 2 is a top plan view thereof;

FIG. 3 is a rear view thereof;

FIG. 4 is a side view thereof, the unshown opposite side being of mirror-image appearance;

FIG. 5 is a front view thereof; and,

FIG. 6 is a bottom view thereof.

The broken line showing of the bedpan in the Figures is for illustrative purposes only and forms no part of the claimed design.
